INVENTOR:
Charles L. Tuttle,
By C. B. Whitmore, Atty.

UNITED STATES PATENT OFFICE.

CHARLES L. TUTTLE, OF ROCHESTER, NEW YORK.

EARTH-AUGER.

No. 833,354.

Specification of Letters Patent.

Patented Oct. 16, 1906.

Application filed January 22, 1906. Serial No. 297,305.

To all whom it may concern:

Be it known that I, CHARLES L. TUTTLE, of Rochester, in the county of Monroe and State of New York, have invented a new and useful Improvement in Earth-Augers, which improvement is fully set forth in the following specification and shown in the accompanying drawings.

My present invention is intended as an improvement upon the post-hole auger shown and described in Letters Patent No. 645,222, issued to me March 13, 1900.

The improved earth-auger herein shown and set forth is more simple in construction than the one described in said Letters Patent, more durable, and less liable to break or give out at the lower part of the shaft.

One object of my present invention is to construct the auger with parts more simple and durable than shown in said Letters Patent.

Another object of the invention is to construct the spiral draw-bit with a quick twist and independent of the shaft and pass it upwardly through the head of the auger and connect it with the shaft above the head.

Other objects and advantages of the invention will be brought out and made to appear in the following specification and the novel construction more particularly pointed out in the appended claims, reference being had to the accompanying drawings, which, with the reference characters marked thereon, form a part of this specification.

Figure 1 is a plan of the auger with the shaft transversely sectioned and a part broken away. Fig. 2 is a view of the auger from beneath. Fig. 3 is a side elevation of the device seen as indicated by arrow 3 in Fig. 1, a part being shown in two positions by full and dotted lines. Fig. 4 is a side elevation seen as indicated by arrow 4 in Fig. 1, a part being axially sectioned and a part broken away. Fig. 5 shows the gimlet-point or bit and the head-bar, with other parts omitted, parts being broken away and centrally longitudinally sectioned. Fig. 6, drawn to a small scale, shows the upper end of the shaft and the handle, parts being broken away and longitudinally sectioned.

Referring to the drawings, G represents the head of the auger, it being substantially circular in plan, comprising a horizontal head-bar A diametrically disposed. To the under flat surface of the head-bar and at the end portions thereof are secured by bolts a

two oppositely-disposed horizontal blades or cutters B B'. The bar A is commonly formed with a hub b, pierced centrally by the bit C, which is threaded in the bar, so as to be coaxial with the head G and longitudinally adjustable therein. The bit extends above the bar A and has upon its upper end an internally-threaded coupling or sleeve d, adapted to receive within its upper end the lower threaded end of a stake or shaft D for turning the auger. The shaft D is hollow, as of gas-pipe, and of a length to have its upper end in convenient reach of the operator, the upper end being provided with a horizontal hollow handle T, Fig. 6, similar to that shown in said Letters Patent, for turning the auger. The shaft D and the bit C are coaxial and have their adjacent ends closely abutting within the sleeve d, as clearly shown in Fig. 4, the said threaded parts A, C, d, and D being firmly screwed together or so rigidly turned against one another as to constitute practically a single solid piece.

Above the cutters B B' are placed a pair of 80 sectoral quadrant plates E E', Fig. 3, alternated with the cutters in the plane of the head G, the plates overlapping at their edges the cutting edges of the blades. There are spaces c c between the plates and the associated cutters, the plates being straight or flat and held to the upper side of the bar A by hinges e e, Figs. 1 and 4, on opposite sides of the bit C. The cutters are formed at their extreme outer edges with upturned lips f f, 90 Figs. 1, 3, and 4, upon which the respective plates E E' rest at their outer edges, as shown.

The bit C is made hollow at its upper threaded end, as clearly shown in Fig. 5, 95 which, with the hollow shaft D, forms a passage for the downflow of air through them, opening out through perforations g (see also Fig. 3) in the bit below the head G. This is to assist when withdrawing the loaded auger 100 from the hole formed in the ground. The spiral-pointed end of the bit is also formed thin and flat and with a quick turn or twist, as shown, which serves better to draw the auger downward when boring than the slow 105 threaded conical point employed in the auger shown and set forth in the Letters Patent above mentioned. This flattened form of the spiraled part of the bit, with rapid lead of twist, causes the bit to hold within its open 110 roomy spirals a large mass of earth and so get a better hold upon the ground when boring.

2
What I claim as my invention, and desire to secure by Letters Patent, is—

1. An earth-auger comprising a circular head having a diametral bar with cutters secured thereto, and plates held by the bar overlapping the cutters, the bar having an axial threaded opening, and a spiral bit with threaded portion projecting upward through the bar, a threaded sleeve on the bit above the bar, and a shaft with threaded end inserted in the sleeve, the ends of the shaft and the bit abutting above said bar, and a handle on the shaft.

2. An earth-auger comprising a circular head having a diametral bar with axial opening, a spiral bit threaded through said opening, a sleeve on the bit and a shaft in the sleeve coaxial with the bit and abutting thereagainst, said bar, the shaft, the sleeve and the bit being joined rigidly as a single body, a pair of sectoral cutters secured to the under side of the bar on either side of the bit, and a pair of straight sectoral plates secured movably on the upper side of the bar on either side of the bit and resting upon portions of the respective cutters, and a handle

for the shaft, there being a passage for the flow of air through the shaft and associated parts, leading out below the head.

3. An earth-auger having a circular head 30 with a diametric bar, a pair of cutters secured to the under surface of said bar, a pair of sectoral quadrantal plates secured to the upper surface of said bar above the cutters and at their edges overlapping the cutting edges of the 35 cutters with spaces between said plates and cutters, said cutters being formed at their extreme outer edges with upturned lips upon which said plates at their outer edges rest, hinges connecting said plates to the bar, a 40 sleeve, a bit having a spiral point and a threaded portion engaged in said bar and sleeve, and a handle having a threaded shaft engaged in said sleeve.

In witness whereof I have hereunto set my 45 hand, this 18th day of January, 1906, in the presence of two subscribing witnesses.

CHARLES L. TUTTLE.
